DESIGN FOR A SERVICE CABLE CONNECTION BOX

Emil T. Hagist, Glenside, Pa.

Application April 30, 1941, Serial No. 100,706

Term of patent 7 years

To all whom it may concern:

Be it known that I, Emil T. Hagist, a citizen of the United States, residing at Glenside, in the county of Montgomery and State of Pennsylvania, have invented a new, original, and ornamental Design for a Service Cable Connection Box, of which the following is a specification, reference being had to the accompanying drawing, forming part thereof.

Fig. 1 is a top plan view of a service cable connection box showing my new design.

Fig. 2 is a front elevation of the same.
Fig. 3 is a bottom plan view of the same.
Fig. 4 is a rear elevation of the same.
Fig. 5 is a view in end elevation of the same.

I claim:

The ornamental design for a service cable connection box, as shown.

EMIL T. HAGIST.
